UNITED STATES PATENT OFFICE.

JAMES HENRY HOLLAND, OF STUTTGART, ARKANSAS.

AUTOMATIC FUEL-SUPPLY-REGULATING MEANS FOR HYDROCARBON-BURNERS.

1,391,956.

Specification of Letters Patent. Patented Sept. 27, 1921.

Application filed June 26, 1919. Serial No. 306,872.

To all whom it may concern:

Be it known that I, JAMES HENRY HOLLAND, a citizen of the United States, residing at Stuttgart, in the county of Arkansas and State of Arkansas, have invented certain new and useful Improvements in Automatic Fuel-Supply-Regulating Means for Hydrocarbon-Burners, of which the following is a specification, reference being had 10 therein to the accompanying drawing.

This invention relates to improvements in automatic fuel supply regulating means for hydrocarbon burners.

The object of the invention is to provide 15 automatic fuel feeding means for hydrocarbon burners adapted to maintain the liquid fuel at a fixed level in the burner or burners at a point near to the wick level thereof whereby a more steady, hotter flame, with 20 substantially total absence of smoke, is obtained.

A further object of the invention is to provide an improved automatic fuel supply regulator of a simple and practical form 25 that will be safe and reliable in the operation and equipped with adjusting means capable of being quickly and easily operated from the exterior of the apparatus.

The invention, with other objects and advantages thereof, and the particular construction, combination and arrangement of parts comprising the same will be understood from the hereinafter contained detail description when considered in connection 35 with the accompanying drawings, forming part hereof, and illustrating one embodiment of the invention.

In the drawing is illustrated improved automatic fuel supply regulating means constructed in accordance with the invention, parts being shown in side elevation and in vertical section.

While I have illustrated in the drawing a specific embodiment of the invention, it will, 45 of course, be understood that changes and variations in the particular construction shown, and the carrying out of the invention in other forms, as will appeal to those skilled in the art and falling within the 50 scope of the appended claims may be practised without departing from the spirit of the invention.

The invention comprehends the use of a main reservoir for liquid fuel, such as coal 55 oil or the like, a pressure pipe line for conveying the liquid fuel from the reservoir to

the hydrocarbon burner or burners located at a distance from the main reservoir, and automatic fuel feed regulating means interposed in the pressure pipe line, and adapted 60 to maintain the level of the liquid fuel in the burners at a constant level at a point adjacent the wick level of the burners.

Referring to a detail description of the drawing, 1 designates the main liquid fuel reservoir, 2 the pressure pipe line for conducting liquid fuel from the reservoir 1 to the hydrocarbon burner 3 located at a distance from the main reservoir, for the sake of clearness, only a single burner in this instance, being shown by way of example. Any of the well known and approved types of illuminating and heating hydrocarbon burners may be employed, the burner shown having associated therewith an oil font or reservoir 3'. 3² designates the wick of the burner, the wick level being indicated by the dotted line b—b. Interposed between the burner 3 and the main liquid fuel reservoir 1, is an automatic fuel feeding means comprising a closed casing 4 providing a distributing chamber 5. The bottom wall 5' of the casing has an inlet opening 6 and a valve seat 7 for an automatically acting valve 8 adapted to regulate the admission of liquid fuel to the distributing chamber 5. The valve 8 is provided with a stem 9 slidably and rotatably supported at its upper part in a bearing plug 10 carried at the upper end of a tubular stem 11 secured 90 within the casing 4, the lower end of the tubular stem 11 having a threaded portion 9' engaging a threaded collar 12 on the bottom wall 5' of the casing. The top wall 13 of the casing 5 is formed as 95 a separate part and detachably secured in place, said wall or cover 13 having a threaded depending flange 14 engaging a threaded end portion 15 of the casing, and having a central opening to fit over the bearing plug 10. 16 designates an annular float in the chamber 5 adapted to operate the valve 8 through the medium of levers 17 pivotally mounted intermediate their ends upon the hollow stem 11, the outer end portions of the levers being pivotally connected with the float, the levers at their inner end portions having rounded heads 18 each engaging and held in a groove 19 in a block 20 on the valve stem 9, the vertical walls of 110 the groove preventing said block from turning when the valve stem is operated,

The pressure pipe line 2 is suitably connected with the inlet 6 of the chamber 5, and 21 designates a conduit leading from the upper part of the chamber 5 to the lower 5 part of the reservoir 3' of the burner 3. The regulating means is adapted to feed the liquid fuel to the font or reservoir 3' of the hydrocarbon burner 3 to maintain liquid fuel therein at a substantially fixed or 10 constant level at a point near to the wick level b—b of the burner. In the drawing, the level of the liquid fuel in the reservoir 3' of the burner is indicated by the dotted line a—a, the level of the liquid fuel in the 15 burner reservoir 3' being shown in the drawing about three quarters of an inch below the wick level of the burner, the maintenance of the liquid level at this distance from the wick level having been found to produce 20 good results, although of course as will be understood, the point at which the liquid level in the burner reservoir 3' is maintained may be varied within reasonable limits so long as the same is maintained at a point 25 substantially near to the wick level of the burner. The automatic fuel supply regulating means acting to maintain the level of liquid fuel in the burner reservoir at a point near to the wick level of the burner is of con- 30 siderable practical importance as it results in obtaining a more steady, hotter flame, with substantially total absence of smoke, smoking of the burner, flickering and uneven flame, as commonly encountered in 35 burners in which the wick is solely relied upon to draw up the liquid fuel to the wick level or burning point, being entirely avoided.

The block 20 has a threaded opening en- 40 gaging a threaded portion 9^a of the valve stem 9, an adjustable connection being thus provided between the inner ends of the valve operating levers and the valve stem. The valve stem extends a substantial distance 45 above the top wall 13 of the casing and is provided with an operating knob or finger piece 9². By rotating the valve stem 9 through the medium of the operating knob or finger piece 9², the connection between the 50 valve stem and the inner ends of the valve operating levers can be adjusted, this special construction affording simple means easily and quickly operable from the exterior of the casing to vary and regulate to a nicety 55 the level of the liquid fuel in the burner reservoir relatively to the wick level.

24 designates a safety overflow pipe connected with the upper portion of the chamber 5, the pipe leading to a suitable catch 60 basin. (Not shown.) 25 designates a sediment draw off cock leading from the bottom of the chamber 5.

Any suitable means may be employed whereby the liquid fuel will be forced under 65 pressure through the pressure pipe line 2.

In the drawing, the main liquid fuel reservoir 1 is shown located above the distributing chamber 5 and burner 3, the liquid fuel being fed through the pressure pipe line by gravity.

What I claim is:

1. The combination with a hydrocarbon chamber, a liquid fuel reservoir and a pressure pipe line for conveying liquid fuel from the reservoir to the burner, of automatic fuel supply regulating means including a closed casing providing a fuel distributing chamber having an inlet opening in its bottom wall, said pressure pipe line leading to said opening, a conduit leading from the chamber to the reservoir of the hydrocarbon burner, a reciprocating valve for the inlet opening in the bottom of the chamber provided with a valve stem extending through the top wall of the casing a substantial distance outside of the same and provided with an operating knob or finger piece, the valve stem having a threaded portion intermediate its ends, a block having a threaded opening adjustably engaging the threaded portion of the stem, 90 a guide on the casing and slidably supporting the upper part of the valve stem, an annular float in the chamber surrounding the valve stem, a tubular stem extending longitudinally of and secured to the casing, and 95 levers pivoted intermediate their ends to the tubular stem, the outer ends of the levers being pivotally connected with the float and the inner ends of the levers being connected with said block, the connection between the valve operating levers and valve stem being adjustable by the rotation of the valve stem through the operating finger piece or knob on the valve stem.

2. The combination with a hydrocarbon burner, a liquid fuel reservoir, and a pressure pipe line for conveying liquid fuel from the reservoir to the burner, of an automatic fuel supply regulating means including a casing providing a fuel distributing chamber having an inlet opening in its bottom wall, said pressure pipe line leading to said inlet opening, a conduit leading from the chamber to the reservoir of the hydrocarbon burner, a reciprocating valve for the inlet opening in 105 the bottom of the chamber provided with a valve stem projecting a substantial distance outside of the casing, means on the casing supporting the rod for rotary and sliding movement, a float in the chamber, levers pivoted intermediate their ends to a part on the casing the outer ends of the levers being arranged to be engaged by the float, and a rotary adjustable connection between the valve stem and the inner ends of said levers, the 110 connection between the valve operating levers and valve stem being adjustable by the rotation of the stem.

3. The combination with a hydrocarbon burner, a liquid fuel reservoir, and a pipe 115
